UNITED STATES PATENT OFFICE.

GEORGE P. KINGSBURY, OF HOLLIS, NEW YORK, ASSIGNOR TO MERGENTHALER LINOTYPE COMPANY, A CORPORATION OF NEW YORK.

TYPOGRAPHICAL MACHINE.

Application filed April 21, 1928. Serial No. 271,734.

This invention relates to typographical machines, such as linotype machines of the general organization represented in U. S. Letters Patent to O. Mergenthaler No. 436,532, 5 wherein circulating matrices are released by escapements from a magazine or magazines in the order in which their characters are to appear in print and then assembled in line, the composed line transferred to the face of a 10 mold, the mold filled with molten metal to form a slug or line of type against the matrices which produce the type characters thereon, and the matrices thereafter returned through a distributing mechanism to the magazine or 15 magazines from which they started.

In these machines, the magazines are usually mounted in such manner that they may be quickly removed and replaced by other magazines containing different matrix fonts. 20 Before removing a magazine, however, it is customary to lock the matrices therein; in fact, this is necessary when the escapements are separated from the magazine, as otherwise the matrices would be free to escape 25 therefrom. Hence, the commercial machines are equipped with devices which prevent the removal of the desired magazine until the matrices have been first locked therein. In some instances, as when the magazine is lifted out 30 of engagement with the escapements, the locking devices are arranged to prevent the premature raising of the magazine; while in other instances, as when the escapements are lowered out of operative relation to the magazine, 35 the locking devices are arranged to prevent the movement of the escapements as distinguished from that of the magazine. In either case, the locking devices referred to are controlled and actuated by matrix locking 40 means which, in locking the matrices in the magazine, release it for removal. There are two kinds of matrix locking means now in use, one being in the form of a detachable bar which is inserted and removed endwise 45 through the edge of the magazine, and the other being in the form of a permanently attached bar mounted on the magazine so as to be movable instantly to active or inactive position.

50 The present invention contemplates a matrix locking bar of the permanent type which not only presents all the advantages of those now in use but may be produced at a minimum cost to the manufacturer and is readily

applicable to all standard linotype magazines including those outstanding. To this end, the improved bar is journaled in the magazine so as to be capable of rotation to lock and release the matrices therein and mounted for bodily movement endwise to actuate the magazine locking device, means being also provided for locking the bar against rotation and endwise movement in its active and inactive positions.

In the accompanying drawings, the invention has been shown merely in preferred form and by way of example but obviously many alterations and variations may be made therein and in its mode of application which will still be comprised within its spirit. It is therefore to be understood that the invention is not limited to any specific form or embodiment except in so far as such limitations are specified in the claims.

Referring to the drawings:

Fig. 1 is a side elevation, partly in section, 75 showing in full lines a magazine and parts immediately associated therewith in their normal position, and in dotted lines the magazine raised to its removing position;

Fig. 2 is a top plan view of Fig. 1;

Fig. 3 is an enlarged vertical section taken on the line 3—3 of Fig. 2;

Fig. 4 is a view similar to Fig. 3 showing the bar in its active position;

Fig. 5 is an end view taken from the right-hand side of Fig. 4;

Fig. 6 is a top plan view of Fig. 5;

Fig. 7 is a detail end view of the bar and its operating handle, showing the relation of the former to the matrices in its active and inactive positions; and

Fig. 8 is a detail view of the opposite end of the locking bar.

The matrices X (see Fig. 1) are stored in the standard magazine A and are released, 95 one at a time, under control of the escapements B which are actuated in the usual way from the regular keyboard mechanism, not shown. The magazine A comprises, as usual, the upper and lower grooved plates A¹, A² and the right and left-hand side bars A³, A⁴, which latter are provided near their lower ends with the customary transverse cuts or recesses A⁵, A⁶. At the front, the respective plates A¹, A² are extended by means of the heavier plate sections A⁷, A⁸ which are also fastened to the side bars A³, A⁴, the upper section A⁷ being adapted to accommodate the matrix locking 100 105

device, and the lower section A^8 being recessed and apertured to receive the grooved portions of the escapement supporting bar B^1 .

In the embodiment illustrated, the escapement bar B^1 is carried by the magazine base frame C , and the magazine is mounted so as to be capable of being lifted out of engagement therewith preparatory to its removal. Consequently, the safety locking device herein employed is associated with the magazine rather than with the escapements and is intended to prevent raising of the former until the matrices have been locked therein. This device is arranged, as usual, at the left of the magazine adjacent the side bar A^4 and consists of a latch member or lever D which is disposed in the longitudinal plane of the magazine and pivotally mounted in a suitable bracket D^1 fastened to the base frame C . A light compression spring D^2 , seated in the bracket D^1 and engaging the latch D , serves to maintain the latter resiliently in its active position, the rear end thereof at such time being directly opposed to a finger E which is adapted to be swung forwardly as the magazine is lifted out of engagement with the escapements B . The finger E is secured to a rock shaft E^1 journaled transversely in the base frame C and provided about midway its length with a rectangular cam plate E^2 which is normally disposed in the plane of the base frame C in position to directly engage a longitudinal bar A^9 fast to the magazine ribs A^{10} . As thus arranged, by rocking the shaft E^1 , the cam plate will be swung upwardly and downwardly and, through its engagement with the bar A^9 , will raise and lower the magazine relatively to the base frame and the escapement bar B^1 (see the dotted line showing in Fig. 1). Rocking of the shaft E^1 is effected, as usual, by means of a pair of manually operable side arms E^3 which are detachably mounted on its opposite ends and may be locked thereto in any suitable manner in order to obtain the purchase required. These arms are adapted to bank upon lateral projections C^1 of the base frame C when swung forwardly to raise the magazine and, in this position, serve not only to support the magazine during its removal but also to facilitate its replacement. The foregoing parts and their mode of operation are similar to those incorporated in the commercial linotype machines and in themselves constitute no part of the present invention, but for further information reference may be had to the McNamara Patent No. 1,586,316.

The present invention is directed specifically to improved means for locking and releasing the matrices in the magazine A and to the manner in which it is adapted to control the operation of the magazine locking device D . Such means, in the preferred embodiment illustrated, consists of a locking bar F provided at its opposite ends with trunnions F^1 , F^2 journaled in the upper plate section A^7 .

To permit the assembling of these parts, the plate section A^7 is provided at one end with a split bearing formed by a block A^{11} and adapted to receive the trunnions F^1 of the bar F . This block A^{11} fits against the right-hand end of the plate section A^7 and is rigidly clamped upon the magazine side bar A^3 by the two screws ordinarily employed to secure that side of the top plate section. For reasons presently to appear, the block A^{11} is provided with a spring detent A^{12} disposed parallel to the locking bar and it is also formed with a transverse slot A^{13} offset at A^{14} . As shown in the drawings, the form and arrangement of the bar F is such that it is adapted, when rotated through a limited number of degrees in a clockwise direction (according to Fig. 7), to stand clear of the matrices in the magazine and, when given a similar turn in the opposite direction, to engage the upper ears of the matrices and push them slightly back out of engagement with the escapement pawls. In the latter or active position of the bar, the matrices are locked thereby against escape from the magazine A .

Rotation of the locking bar, in the present instance, is accomplished by means of a small operating handle F^3 keyed to the trunnion F^1 , and having a hub portion F^4 formed with a short radial arm F^5 , the latter being disposed approximately at right angles to the shank portion F^6 of said handle and located in a plane offset slightly therefrom. In the inactive position of the bar F (see Fig. 3), the handle F^3 is raised and the shank portion F^6 thereof lies flush against the outer side face of the bearing block A^{11} where it is maintained yieldingly by the spring detent A^{12} . When the bar is turned to its active position (see Fig. 5), the shank portion F^6 of the handle F^3 is first brought into registry with the slot A^{13} , above mentioned, where it is arrested by a stop shoulder a formed on the block A^{11} . This operation also swings the radial arm F^5 upwardly into horizontal alignment with the detent A^{12} . As before stated, the bar F is not only rotatable to lock the matrices in the magazine but is also capable of a limited endwise movement to actuate the latch D . The block A^{11} is, therefore, counter-bored to receive the hub portion F^4 of the handle, and the bar proper between the trunnions F^1 , F^2 is made somewhat shorter than the distance between the inner side walls of its bearings. Hence, when the handle is in registry with the slot A^{13} , the bar is capable of being slid bodily endwise back and forth in its bearings.

As best shown in Figs. 2, 3, and 4, the front end of the latch D lies directly in the path of the bar F so as to be engaged by the trunnion F^2 thereof and rocked about its pivotal axis when the bar is shifted toward the left. In order, however, to provide a better engagement between these parts, a stud f is screwed into the end of the trunnion F^2 and is ar-

ranged to engage the latch below the rounded or beveled corner d thereof. When the bar is pushed all the way to the left to actuate the magazine latch, the shank F^6 of the handle

- 5 F^3 is vertically alined with the notch or offset portion A^{14} of the slot A^{13} and may then be lifted into engagement therewith to lock the bar against endwise movement. In this connection, it should be understood that sufficient
10 lost motion of the bar in its locking position is necessary to permit such axial movement thereof to take place without disturbing its purchase on the matrices. As the shank of the handle enters the notch A^{14} , the detent
15 A^{12} engages a recess in the short radial arm F^5 and thus maintains the bar F in its locked position (see Figs. 4, 5 and 6).

From the foregoing, it will be seen that, when the bar F has been pulled to the right

- 20 against the inner wall of its right-hand bearing, it may be turned to active or inactive position as desired, according to the direction of movement of the operating handle F^3 . In the inactive position of the bar, the handle
25 F^3 is raised alongside the outer face of the bearing block A^{11} and locks the bar against endwise movement. In the active position of the bar, on the other hand, the handle stands opposite the slot A^{13} and allows the
30 bar to be pushed to the left, in which position it may be locked against endwise movement by turning the handle upwardly to cause its shank F^6 to enter the offset portion A^{14} of the slot A^{13} . The detent A^{12} serves, in both its active and inactive positions, to restrain the
35 bar against accidental rotation. Since endwise movement of the bar is permitted only when it is in active position, any damage that might occur for failure to lock the matrices
40 before the release of the magazine is avoided. It is also pointed out that, inasmuch as the extent of the endwise movement of the bar F in operating the magazine latch D is greater than the distance between the inner walls of
45 the magazine side bars and the adjacent columns of matrices, the arrangement must be such as will permit rotation of the bar in overlapping relation to said bars in order that all of the matrix columns may be engaged
50 whether the bar occupies its position at the left or right. For this reason, and as will be seen from Figs. 3, 4, and 5, the locking bar, in the present instance, is preferably arranged in definite relation to the regular transverse
55 cuts or recesses A^5 , A^6 ; that is to say, the axis of the bar F is located centrally above these cuts so as to provide the necessary clearance without changing the construction of the
60 standard magazine.

- While the operation of the parts will have been understood from the foregoing description, a brief recapitulation may be helpful. Preparatory to removing the magazine A , and assuming the matrices to be unlocked, the handle F^3 is disengaged from the detent A^{12}

and, by the same operation, turned downwardly against the stop shoulder a . The bar F is thus rotated to its active position and is now free to be pushed to the left until the hub portion of the handle comes in contact 70 with the right-hand bearing. The handle is then lifted slightly to lock the bar and permit the detent A^{12} to snap into engagement with the radial arm F^5 (see Figs. 4, 5, 6, and 7). The matrices X are thereby locked against 75 escape and the trunnion F^2 at the left will have engaged the magazine latch D and rocked the upper end thereof out of the path of the upstanding finger E . The magazine may then be lifted, by means of the side arms 80 E^3 and cam plate E^2 , out of engagement with the escapements B to removing position (see dotted lines Fig. 1). As the magazine is raised, the trunnion F^2 is disengaged from 85 the latch D and the latter is allowed to resume its normal locking position under action of the spring D^2 . When the magazine is lowered, however, the stud f on the end of the trunnion F^2 will engage the beveled corner 90 d of the latch D and, by such engagement, cam the latter out of the way so that the magazine may properly reengage the escapements B . After the magazine comes to rest on the base frame C , the handle F^3 is disengaged 95 from the notch A^{14} , pulled toward the right to draw the bar F out of engagement with the latch D and cause it to lock the magazine against removal, and finally turned upwardly until engaged by the detent A^{12} to restore the bar to its inactive position. 100

Having thus described my invention, its construction, and mode of operation, what I claim and desire to secure by Letters Patent of the United States, is as follows:

1. In a linotype machine, the combination 105 with a matrix magazine and a bank of escapements therefor, one of said parts being movable out of operative relation to the other, of a locking device to prevent such relative movement, and a rotatable bar associated 110 with the magazine for locking and unlocking the matrices therein, said bar being arranged to engage the locking device and capable of endwise movement to actuate the same.

2. In a typographical machine, the combination 115 of a removable magazine, a spring-actuated locking device for maintaining the magazine in operative position, and a bar journaled in the magazine and rotatable at will to lock and unlock the matrices therein, said bar being movable endwise to actuate the locking device in effecting the locking and release of the magazine. 120

3. In a typographical machine, the combination 125 of a removable magazine, means for removing the magazine from its operative position to permit its removal, a locking device to prevent the operation of said moving means, a bar journaled in the magazine and rotatable at will to lock and unlock the 130

matrices at will, and means for holding the bar against rotation in its active and inactive positions, said bar in its active position being capable of endwise movement to actuate the aforesaid locking device.

4. In a typographical machine, the combination of a removable magazine, means for moving the magazine from its operative position to permit its removal, a locking device 10 to prevent the operation of said moving means, a matrix locking bar movable endwise to actuate said device and rotatable to lock and unlock the matrices in the magazine, and means for locking the bar against 15 rotation and endwise movement in its active and inactive positions.

5. In a typographical machine, the combination of a removable magazine, means for moving the magazine from its operative position to permit its removal, a locking device to 20 prevent the operation of said moving means, a matrix locking bar movable endwise to actuate said device and rotatable to lock and unlock the matrices in the magazine, a handle 25 for operating the bar, and means arranged to engage the handle for holding the bar against rotation and preventing endwise movement thereof in its active and inactive positions.

30 6. In a typographical machine, the combination of a removable magazine, means for moving the magazine from its operative position to permit its removal, a locking device to

prevent the operation of said moving means, a matrix locking bar movable endwise to actuate said device and rotatable to lock and unlock the matrices in the magazine, a handle for operating the bar, and a detent arranged to engage the handle for holding the bar against rotation in its active and inactive 40 positions.

7. In a linotype machine, the combination with a matrix magazine having side bars formed with notches, and a bank of escape- 45 ments therefor, one of said parts being mov- able out of operative relation to the other, of a locking device to prevent such relative movement, and a matrix locking bar rotat- ably mounted in the magazine and capable of endwise movement to actuate said locking de- 50 vice, said bar being arranged centrally above the notches of the magazine side bars, for the purpose described.

8. A linotype magazine provided with a 55 matrix locking bar movable endwise and ro- tatably mounted therein, a handle for operat- ing the bar, and means for locking the bar against rotation and endwise movement in its active and inactive positions.

9. A structure as specified in claim 1 char- 60 acterized by the fact that the endwise move- ment of the matrix locking bar is permitted only when it occupies its active position.

In testimony whereof, I have affixed my signature hereto.

GEORGE P. KINGSBURY.
